UNITED STATES PATENT OFFICE.

THEODORE P. BROWN, OF WORCESTER, MASSACHUSETTS.

PNEUMATIC MOTOR FOR MUSICAL INSTRUMENTS.

SPECIFICATION forming part of Letters Patent No. 594,981, dated December 7, 1897.

Application filed March 17, 1897. Serial No. 627,930. (No model.)

To all whom it may concern:

Be it known that I, THEODORE P. BROWN, a citizen of the United States, residing at Worcester, in the county of Worcester and 5 State of Massachusetts, have invented a certain new, useful, and valuable Improvement in Pneumatic Motors for Musical Instruments, of which the following is a full, clear, and exact description:

My invention relates to pneumatic motors for musical instruments, and particularly to that class of motors which are employed in self-playing musical instruments; and the object of my invention is to provide a more practical and efficient motor than any heretofore used.

In the accompanying drawings, which form a part of this specification, Figure 1 is a front elevation of my complete motor. Fig. 2 is a transverse vertical section of the same, taken through line 2 2 of Fig. 1. Fig. 3 is a longitudinal horizontal section taken through line 3 3 of Fig. 1, but showing only my slide-valve mechanism and connecting channel-board.

Numerals of reference are placed upon or connected to the numerous parts shown in the drawings, like numerals of reference indicating the same parts throughout the several views, and in the following detailed description corresponding numerals will be employed to indicate the parts referred to.

The entire motor mechanism is supported from the foundation-board 1 by legs 2, secured at their upper ends to the channel-board 3. Said channel-board 3 has a longitudinal channel or chamber 4 extending nearly its entire length, being closed at one end and in communication with a tube or pipe 5^a at its opposite end. Through the front of said channel-board 3 are three equidistant apertures or ports 5, leading into the chamber 4, and directly under these are three other ports 6. Communicating with the main or longitudinal channel 4 in the channel-board 3 are three supplemental air channels or ports 7, which extend entirely through the said channel-board 3 and through their respective fixed bellows-boards into the bellows 9, having the movable board 10. Working in guide-rails 11 are three sliding valve-boards 12, connected to three differential cranks 13 14 15 in the shaft 16 by their pitman-rods 17, and said valve-

boards 12 having recesses 18 formed in their inner surface. The function of said recess 18 in each valve-board is to connect the ports 5 and 6, so that when the valve-board is lowered the recess 18 connects the upper port 5 and lower port 6, so that if the chamber 4 is kept under air-pressure, as in practice, it acts through the port 5, valve-board recess 18, 60 port 6, channel 7, and port 8 upon the bellows 9, thus causing the closed bellows to expand. The pitman 19 is pivotally connected at one end to the cleat 20 on the bellows-board 10 and at the opposite end to the crank 15, formed in shaft 16, it being noted that each valve-board pitman 17 is pivotally secured to an extension-block 21 upon the said pitman 19, thus obviating more than three crank-bends 15 in the shaft 16. 70

The operation of my improvements are obviously as follows: The pipe 5^a is extended to a pressure-bellows or other suitable device, which steadily impels air therethrough and keeps the channel 4 under pressure and tending to communicate with and expand the three bellows 9, as before described; but it can only act on the one bellows which happens to be collapsed or closed, because it is only when a bellows is closed that its slide-valve 12 is 80 in the proper position to allow the air to pass from the chamber 4 through the recess 18 into the particular closed bellows 9, which in turn acts upon the pitman-rod 19 to revolve the shaft 16, and thus bring another bellows into 85 a closed position ready to be expanded, and so on until the third bellows is brought into a closed position, whereupon each bellows in turn acts partially to revolve the main shaft 16. When any particular bellows has been 90 expanded to its full extent, the recess 18 in the slide-valve 12 has uncovered the port 6, which allows the compressed air within the bellows to escape and allows the bellows to be closed freely, as is clearly shown in Fig. 2. 95

My motor mechanism can be operated under the exhaust system simply by keeping the chamber 4 exhausted and arranging the slide-valve 12 to connect the chamber 4 with a particular bellows when the latter is opened to 100 its fullest extent when the suction of air therefrom serves to close it. For most purposes the exhaust system is preferable.

By the successive operation of the three

bellows in the manner described a perfectly regular and uniform revolution is given the main shaft 16, the speed of revolution depending entirely upon the degree of pressure or 5 exhaust at which the chamber 4 is kept, and this may be regulated in many ways.

In order to propel the music-roller 22, I hinge or otherwise rock or make it movable, so that its pinion 23 can readily be thrown 10 into or out of mesh with a pinion 24, fixed upon one end of said revoluble shaft 16.

Having now described my invention and stated the manner in which it is to be used, what I claim as new, and desire to secure by 15

Letters Patent, is—

In a pneumatic motor, the combination with a channel-board having main and supplemental air-channels, each opening outward through the front face of the board, of three

or more bellows arranged upon the rear face of the channel-board and each bellows having an air-passage leading to one of the supplemental air-channels, a crank-shaft having a number of crank-arms corresponding to the number of bellows, an independent pitman connecting each crank-arm and bellows, slide-valves each having a recess adapted to move over the openings in the face of the channel-board, and an independent pitman connection between each slide-valve and crank-arm, substantially as described.

In testimony whereof I affix my signature in the presence of two witnesses.

THEODORE P. BROWN.
